UNITED STATES PATENT OFFICE.

RICHARD H. BARNITZ, OF WASHINGTON, DISTRICT OF COLUMBIA.

MAIL-BAG CATCHER.

1,416,932.

Specification of Letters Patent. Patented May 23, 1922.

Application filed December 16, 1920. Serial No. 431,149.

To all whom it may concern:

Be it known that I, RICHARD H. BARNITZ, citizen of the United States, residing at Washington city, in the District of Columbia, have invented certain new and useful Improvements in Mail-Bag Catchers, of which the following is a specification.

This invention relates to mail bag catchers and the devices for mounting the same upon the door frames of mail cars, and it has for its object the production of a fork and mounting comprising parts of special construction and arrangement whereon the fork, always relatively heavy and cumbersome to handle, may be partially supported both while placing the same in operating position, and upon removing the same from the door of the car.

This invention consists of locks or carriers pivotally supported upon the frame of the car door and having passages permitting the longitudinal and rotary movement of the straight end portions of the fork, with devices for limiting those movements, as well as for stopping the horizontal movements of the blocks in either direction at predetermined points.

In the accompanying drawings the construction and arrangement of the parts of this invention are illustrated, and Fig. 1 represents the frame of a car door to which this invention has been applied. The view is taken looking towards the door. Fig. 2 is a somewhat enlarged view of one of the supporting or fork-mounting devices shown in Fig. 1, a portion of the block being broken away to disclose the passage through it for the passage of the straight end portions of the fork. Fig. 3 is a horizontal cross-section of the car door frame showing one side thereof somewhat enlarged with the device for holding the fork constructed in accordance with this invention applied thereto. This view is taken upon the broken line 3-3 of Fig. 1. Fig. 4 is a horizontal cross section on the broken line 4-4 of Fig. 1 of one side of the car door frame showing this invention attached thereto and also in section. Fig. 5 is a side view of one of the mounting devices shown on the right hand side in Fig. 1, the fork being removed, and the view being taken from the left hand side of the device. Fig. 6 is a like view of the same mounting device shown in Fig. 5, the view being taken from the right hand side, and the butt end of the straight portion of

the fork being shown in the mounting. In all the figures after Fig. 1 the scale of drawing has been increased to better illustrate the parts described.

Throughout the drawings and description, the same letter is used to refer to the same part.

Considering the drawings, the car door frame A has shown across it a mail bag catcher fork of the usual pattern, comprising the straight or straight-ended portion B, the inclined and outwardly extending portion C, and a rubber cushion c encircling the end portion next to the mounting as set out in Fig. 1.

The straight portion of the fork is mounted upon the car door frame by means of devices comprising each a plate or base D, carrying a pivot pin d which passes through flanges E, e projecting from the plate D, and through the block F that is pivotally held by the pin between the said flanges. The block may be swung out and in horizontally. As best shown in Fig. 2 the block F has the passage f extending through it to permit the longitudinal and rotary movements of the straight member or portion of the fork marked B. Each of the pivoted blocks or carriers described herein has a stop such as the stop G best shown in Fig. 2, and a strike end g such as best shown in Fig. 4, and the frame of the car door or some adjacent portion may be provided with the rubber cushion H with which the strike g contacts. That contact limits the horizontal movement of the block F in one direction, and the stop h best illustrated in Fig. 4 shows one method of stopping the movement of the block in the other direction.

Considering Figs. 5 and 6 there will be noted the mounting or fork-supporting device shown on the right hand side of the car door frame in Fig. 1. As explained for the first mentioned mounting, this device comprises a plate or base J, having a pivot pin j passing through flanges K and k projecting from the plate and through the block or carrier L which block may thus be swung horizontally out and in upon the pin. The passage through the block L for the straight end of the fork is marked M, and it has a slot m running lengthwise through it. The passage M is intended to movably admit the butt end portion N of the straight portion B of the fork, and it will be noted that the butt has a lug n which is constructed to pass

through the slot *m* and free the butt end of the fork when the end is turned into the proper predetermined position. The lug *n* of the butt *N* also meets the stop *O* which 5 is carried by the block *L* in the path of the lug *n*. The stop *O* is alike in position, formation and function to the stop *G* previously mentioned herein.

To explain the operation of this invention, let it be assumed that the fork is in the position illustrated in Fig. 1, that is to say, the handle *b* is in a vertical position, and the inclined member *C* hangs down against the car door frame. When it is desired to 10 catch a mail bag, the handle *b* is grasped, and the fork turned until the inclined member *C* projects outwardly from the car door. The fork is now in catching position, and when it reaches that attitude, the lug *n* 15 meets the stop *O* and the fork is stopped and may be held at the proper place for the purpose of catching the bag. Next, let it be assumed that it is desired to remove the fork from the car door. The butt is turned until 20 the lug *n* may be passed through the slot *m* in the passage *M* of the pivoted block *L*. The straight portion of the fork *B* is now moved to the left until the butt *N* is free from the block *L*. It will here be noted that 25 the end of the straight portion *B* of the fork is supported by the block *F* and a considerable part of the weight of the fork is still carried by that block. The operator now 30 moves the butt of the form into the car, the block *F* swinging correspondingly, and withdraws the end of the fork. In replacing the 35 fork the end of the straight portion *B* is again introduced through the block *F* and a considerable part of the weight of the fork 40 is thereby supported while it is being remounted upon the car door frame *A*. When the block *F* swings inwardly towards the car, its movement is limited by contact with the angular stop *h*, shown in Fig. 4, and 45 when the block is swung outwardly the strike end *g* and rubber cushion *H* meet as stated.

Having now explained this invention and the mode of its operation, what I claim is:—
50 1. In a mail bag catcher, the combination with a fork having a straight portion, of devices for mounting the fork by engagement with said straight portion comprising a plate or base having projecting flanges, a 55 block pivotally supported between the

flanges of the plate and having a passage admitting the said straight portion of the fork and whereon the fork may be swung into the car, means for supporting the butt of the said straight portion of the fork, the said supporting means and the said butt having devices for limiting the rotary and longitudinal movements of said butt.

2. In a mail bag catcher, the combination with a fork having a straight portion, of devices for mounting the fork by engagement with said straight portion comprising a plate or base, a block pivotally supported by the said plate and having a passage admitting the said straight portion of the fork 60 and whereon the fork may be swung into the car, means for supporting the butt end portion of the fork, the said supporting means and the said butt having devices for limiting the rotary and longitudinal movements of 65 the butt.

3. In a mail bag catcher, the combination with a fork having a straight portion, pivotal means for supporting the end of the said straight portion whereon the fork may 70 be swung into the car, the said supporting means having a passage permitting the longitudinal movement of the said straight portion of the fork, means for mounting the butt end of the said straight portion comprising a plate or base, a block pivotally supported by the plate and having a passage admitting the said butt, the said supporting means and the said butt having devices for 75 limiting the rotary and longitudinal movements of the said butt.

4. In a mail bag catcher, the combination with the fork having a straight portion, pivotal means for supporting the end of the said straight portion whereon the fork may 80 be swung into the car, means for mounting the butt end of the said straight portion of the fork comprising a plate or base, a block pivotally supported by the said plate and having a passage admitting the said butt, the said supporting means and the said butt having devices for 85 limiting the rotary and longitudinal movements of the said butt.

4. In a mail bag catcher, the combination with the fork having a straight portion, pivotal means for supporting the end of the said straight portion whereon the fork may 90 be swung into the car, means for mounting the butt end of the said straight portion of the fork comprising a plate or base, a block pivotally supported by the said plate and having a passage admitting the said butt, the said supporting means and the said butt having devices for 95 limiting the rotary and longitudinal movements of the said butt.

In testimony whereof I affix my signature.
RICHARD H. BARNITZ.
